G. JURESISIN

MOTOR OPERATED DRILL

Filed June 18, 1923

FIG. 1.

FIG. 2.

३३१

J. R. Bryant.

Attorney.

UNITED STATES PATENT OFFICE.

GEORGE JURESIKIN, OF WILKES-BARRE, PENNSYLVANIA.

MOTOR-OPERATED DRILL.

Application filed June 18, 1923. Serial No. 646,280.

To all whom it may concern:

Be it known that I, GEORGE JURESIKIN, a citizen of Czechoslovakia, residing at Wilkes-Barre, in the county of Luzerne and State of Pennsylvania, have invented certain new and useful Improvements in Motor-Operated Drills, of which the following is a specification.

This invention relates to certain new and useful improvements in motor operated drills and has particular reference to the construction of a fluid operated motor, preferably designed to be operated by air pressure.

15 An object of the invention resides in the provision of an air motor for operating drills and the like, wherein the rotor within the motor casing has one side thereof spaced from an offset portion of the casing to provide a relatively long arcuate passage traversing the transverse axis of the rotor with a partition therein associated with the inlet controlling valve for the supply of air causing the air to travel tangentially in 25 either direction for reversely rotating the rotor.

Another object of the invention resides in an air motor of the type above set forth having an eccentric mounting for a drill 30 supporting socket within the casing of the motor with meshing gears establishing communication between the drill supporting socket and the bearing shaft of the rotor. With the above and other objects in view 35 as the nature of the invention is better understood, the same consists of the novel form, combination and arrangement of parts hereinafter more fully described, shown in the accompanying drawing and 40 claimed.

In the drawing, wherein like reference characters designate corresponding parts throughout the several views,

Figure 1 is a longitudinal sectional view 45 taken on line I—I of Fig. 2, and

Figure 2 is a cross-sectional view taken on line II—II of Fig. 1.

Referring more in detail to the accompanying drawing, there is illustrated an air 50 motor for operating drills and the like com-

prising a motor casing having an end wall 1 carrying a depending side wall 2 that is offset at one side thereof as at 3 to provide lateral passages 4 each extending substantially one quarter of the way around the 55 motor casing upon opposite sides of a transverse axis thereof. The offset portion 3 of the motor casing has an inlet connection 5, while a diametrically positioned outlet 6 is carried by the side wall 2 of the casing. The 60 inlet connection 5 carries a manually operable valve 7 controlling the passage of air through the connection 5 as will at once be obvious from an inspection of the drawing.

An arcuate partition wall 8 is preferably 65 formed integral with the motor casing, the same being positioned adjacent the offset portion 3 and spaced therefrom as shown in Fig. 1 to provide inner walls for the lateral air passages 4, the inner curved face of the 70 partition 8 cooperating with the inner face of the casing wall 2 to form a complete circle. The partition wall 8 intermediate its ends, carries an outwardly directed abutment wall 9 that is engaged by a side face 75 of the valve plug 7 to cooperate therewith for closing one of the passages 4, as shown in Fig. 1, when air passing through the connection 5 enters the other passage.

A rotor is journaled in the casing, the peripheral edge thereof wiping the inner face of the side wall 2 and the inner face of the partition 8 as shown in Fig. 1, the rotor comprising a disk plate 10 provided with a central boss 11 that carries a bearing stub 85 shaft 12 projecting from opposite sides of the plate 10, the end wall 1 of the casing carrying an axial socket 13 in which one end of the bearing shaft 12 rotatably extends with anti-friction bearing balls 14 and a 90 wearing plate 14^a interposed between said end of the bearing shaft 12 and the socket 13. The inner face of the wall 1 carries an annular rib 15 supporting the disk plate 10 adjacent its outer edge, the peripheral edge 95 of the disk plate 10 being of double walled formation, having an inner wall 16 of cylindrical form and concentric with the disk plate and parallel wall 16^a and carrying spaced partitions 16^b having arcuate faces 100

between the walls 16^a forming elongated air pockets 17 that open outwardly as at 18 and having their longitudinal axes extending circumferentially of the plate 10 as shown in 5 Fig. 1. These pockets 17 constitute the buckets of the rotary member, the whole device thus constituting a species of impulse turbine.

The stub shaft 12 supporting the disk 10 plate 10 of the rotor has a gear wheel 19 fixed thereto, and the bearing for the outer end of the shaft 12 includes a disk plate 20 received in the lower open end of the casing as shown in Fig. 2, the plate 20 carrying a 15 socketed boss 21 enclosing anti-friction bearing members for the shaft 12, while a depending annular rib 20^a carried by plate 20 forms a guide for the wall 16 of the rotor. The plate 20 rests on a shoulder formed in 20 the interior of the wall 2, this shoulder being shown in Figure 2 only, as the section line on which Figure 1 is taken lies below said shoulder. A disk 23 is threaded in the upper open end of the casing and carries an 25 eccentric apertured boss 25 in which a tool socket 26 is journaled, the socket 26 rotatably extending through the disk plate 20 and carrying a gear wheel 27 upon the inner end thereof that meshes with the gear 19, rotary 30 motion of the stub shaft 12 being communicated to the tool socket 26 in an obvious manner. To facilitate handling of the motor casing, diametrically opposite handles 28 are carried by the side walls thereof. It will 35 now be seen that the disk 20 holds the rotor in place without jamming as it is supported by the shoulder, the disk 20 being forced firmly against its shoulder by the disk 23.

In the operation of the device, the passage 40 of air under compression through the connection 5 to the motor casing passages 4 is controlled by the valve 7, the air being caused to enter the desired passage therefor at the proper side of the abutment wall 9 as 45 shown in Figure 1, and the open ends 8^a of the arcuate passages 4 terminate at points substantially 90 degrees from the inlet 5 and outlet 6, air flowing through the selected passage and entering the pockets 17 successively and, by its impingement against the far concave faces of said pockets causing the rotor to revolve, the revolution of the rotor through the gear connections between the rotor and the tool socket 26 causing rotation of the latter. The air carried in the 55 pockets 17 is exhausted through the outlet opening 6 as indicated by the arrows in Fig. 1, and any air remaining in the pocket is discharged in the idle passage 4 and exhausted through the opening 3^a in the offset wall 3 of the motor casing. As shown in 60 Fig. 1, the exhaust openings 3^a are selectively closed by the screw plug 29 insuring proper operation of the motor. It will be readily seen from an inspection of Fig. 1 that the

rotor is caused to revolve in either direction under control of the valve 7, the direction of rotation being controlled by the direction of flow of the air through the passages 4. The terminating of the passages 4 substantially 70 90° from the inlet 5 and the forming of these passages on long arcs are believed to cause the motive fluid to be delivered at a suitable angle in respect to the circumferentially elongated pockets 17 and their arcuate 75 end walls to obtain the most power from the fluid.

While there is herein shown and described the preferred embodiment of the present invention, it is nevertheless to be understood that minor changes may be made therein without departing from the spirit and scope of the invention as claimed.

What is claimed as new is:—

1. An air motor for drills comprising a 85 truly cylindrical casing, a truly cylindrical rotor chamber eccentrically formed therein and permanently closed at one end, axially aligned inlet and exhaust ports for said casing with the common axis of said ports intersecting the parallel axes of the casing and rotor chamber at right angles thereto, said exhaust port communicating directly with the rotor chamber, the thickest side of the 90 wall of the casing, formed by the eccentric location of the rotor chamber, having motive fluid feeding passages formed circumferentially therein communicating with and extending in opposite directions in respect to the inlet port, said feeding passages 95 communicating with the rotor chamber at substantially diametrically opposite points, a rotor in said chamber having circumferentially elongated pockets formed in its periphery with the end walls of each pocket 100 formed on an arc, means for closing the open end of said rotor chamber, a tool socket 105 rotatably carried by said means, means for operatively connecting the rotor and tool socket, and means for selectively controlling the communication of the inlet port with the fluid feeding passages for causing rotation 110 of the rotor in opposite directions.

2. An air motor for drills comprising a 115 casing, a cylindrical rotor chamber formed in the casing and permanently closed at one end, an inlet port for the casing having branch feeding passages communicating with the rotor chamber at points spaced around the periphery of the latter, means 120 for selectively controlling the communication of the inlet port with said passages, an exhaust port for the chamber, an annular shoulder formed in the wall of the chamber inwardly of its open end, a disk engaging 125 said shoulder and closing the end of the chamber, axially aligned anti-friction bearings formed in the end wall of the chamber and the disk, a stub shaft journaled in the bearings, a rotor fixed to the shaft and com- 130

prising a circular plate, a ring like margin formed on the plate axially offset toward the disk, and pockets formed in the periphery of the margin, a gear wheel fixed on the 5 stub shaft between the plate and the chamber end closing disk, a member fastened to the casing and holding the disk against its

shoulder, a tool socket having a shank journaled in said member and projecting through the disk, and a gear wheel fixed on 10 the shank and meshing with the gear wheel on the rotor shaft.

In testimony whereof I affix my signature.
GEORGE JURESIKIN.
